UNITED STATES PATENT OFFICE.

GEORGE C. MOORE, OF REVERE, MASSACHUSETTS.

WOVEN FABRIC.

No. 820,515.

Specification of Letters Patent.

Patented May 15, 1906.

Application filed November 23, 1904. Serial No. 234,059.

To all whom it may concern:

Be it known that I, GEORGE C. MOORE, a citizen of the United States, residing at Revere, in the county of Essex, State of Massachusetts, have invented a certain new and useful Improvement in Woven Fabrics, of which the following is a specification, reference being had therein to the accompanying drawing.

10. My invention has for its object an improvement in woven fabrics, and especially in that class of woven fabrics which are known as "double-faced" fabrics.

The invention will be fully understood 15 from the following description, taken in connection with the accompanying drawing, and the novel features thereof are pointed out and clearly defined in the claims at the close of this specification.

20. The accompanying drawing is a conventional figure or diagram illustrative of the construction of my improved fabric.

Although my invention is not limited to fabrics of any special width, I have thus far embodied it in fabrics which are generally termed "narrow" fabrics, such as are made on a narrow-fabric loom. A fabric embodying my invention comprises two or three sections, which may be varied in relative widths, 30 as desired—that is to say, the web has, ordinarily, a central and two side sections, said central section being interlocked with and serving to unite the said side sections. One of the side sections may, however, be omitted. 35 I will describe my invention as embodied in a fabric formed in three sections.

A single shuttle is required, and this shuttle carries the weft-supply for the central section of the fabric. The weft for the side 40 sections comes from two independent supplies, one for each side section. The shuttle traverses the entire width of the web; the shuttle-thread being carried around the thread from the independent source of supply, which provides the weft for each side section. At each flight of the shuttle the weft-supply for one of the side sections is drawn 45 inwardly by the shuttle-thread to a predetermined point in the width of the fabric, covering either face of the fabric, as desired. This point may be determined by means of a warp-thread or a wire, if a wire be employed, as is common in weaving narrow fabrics and the like—that is to say, the loom is 50 arranged in the well-known manner, so that the shuttle-thread will encircle or lock with

a given warp or a wire at a predetermined point in the width of the fabric, and the loop which forms the weft or filling for the side sections will not be drawn inwardly by the 60 shuttle-thread beyond this warp or wire. In this way, as will be clear, if the side section of the fabric is of a different color from the central section a pattern may be formed—that is, the inner edge of the side or colored section may be given any desired shape or contour. As the central section the weft of which is supplied from the shuttle may be relatively narrow, a large quantity of fabric may be woven from one shuttle-supply, and 70 since the weft-supply of the side sections is an independent supply which may come from a large cop or ball a large amount of fabric may be woven without stoppage or delay for a new supply of thread. 75

To make the construction of my fabric as above set forth more clear, I will refer to the accompanying drawing, which represents a diagram illustrative of the construction of a specified kind of fabric embodying my invention—namely, what is known as an "elastic" fabric. In the production of this fabric four wires are employed in the well-known manner. These are designated *a*, *b*, *c*, and *d*. The rubber warp-threads, of which there are fifteen in the particular fabric intended to be illustrated, are designated *f*. The fibrous warp-threads, four in number, which are intermediate the rubber threads, are designated *g*. The three sections widthwise of the fabric, each of which sections is formed by a different weft-thread, comprises a side section *h*, a central section *j*, and another side section *l*. As previously indicated, one of the said side sections may be omitted, in which case the 90 fabric would comprise two sections, one of which would correspond with the central or body section *j* of the diagram and the other with one of the side sections. The weft-thread indicated at *m* is from an independent 95 or outside source of weft-supply, and from this the weft of section *l* is formed. In like manner the thread designated *o* is also from an outside source of weft-supply and forms the weft of the section *h* of the fabric. The 100 weft *p* of the central section *j* is supplied from the shuttle, and, as will be clear, is interlocked, as indicated at *t*, with the weft of section *l* and at the opposite side, as indicated at *w*, with the weft of the section *h*. As previously stated, the shuttle traverses the entire width of the fabric. Suppose it to be 110

moving (pick number 1) in the direction indicated by the arrow and to be laying the weft-thread designated 10. It passes across the fabric and around the thread *o*, which 5 forms the weft of section *h*. The said thread is at the time the shuttle passes around it occupying the position at the side of the fabric which I have indicated by the dotted line 11. The shuttle then passes in the reverse 10 direction, (pick number 2,) drawing in with it the portion 12 of the weft *o* until it reaches the point at which it can no longer draw the said weft *o* inwardly on the under face of the fabric. In the construction illustrated in the 15 diagram this point is reached at the wire *b*, since the shuttle-thread passes around the said wire *b*. The portion 12 of the weft-thread when drawn inwardly passes under the wire *a* and adjoining rubber thread *f*, alternately over and under the four intermediate warp-threads *g*, under the next rubber thread *f*, alternately over and under four more intermediate warp-threads *g*, and so on. The next inwardly-drawn portion of the weft 20 *o*, which I have designated 14, forms the opposite face of the fabric—that is, it passes over the wire *a* and adjoining rubber thread *f*, alternately under and over the binder warp-threads *g*, over the rubber thread, alternately 25 under and over the next group of four warp-threads, under the next rubber thread, and so on. This arrangement is practically duplicated by the warp-thread *m* at the opposite side of the fabric, as will be clear. The 30 same arrangement is also followed in laying the shuttle-weft *p*, thereby securing a visible ground-work of weft from side to side of the fabric and on both faces thereof. The picks are designated at the left of the diagram by 35 the numerals 1, 2, 3, and 4. The picks are repeated in these groups of four.

The outer rubber warps *f* in the side sections are preferably located at the extreme edges of the fabric next the wires *a* and *d*, 40 around which the side-section wefts *o* and *m* pass, so that in the completed elastic fabric the latter will be edged by rubber warps covered only by the side-section wefts, thus affording the desired elasticity for the fabric 45 edges, and by employing somewhat large rubber warps a corded effect may be given to the fabric.

By varying the shedding of the warp-threads in the well-known manner a double-faced fabric may be readily produced which 50 will be exactly alike on both faces, and if the three sections of the weft are of contrasting colors the proximate or meeting edges of each section will be clearly and sharply defined, 55 with the weft forming the visible ground of

the fabric. A fine fabric of handsome appearance may also be produced at a minimum of cost by employing the proper material—as, for example, mercerized thread for the shuttle-filling and silk floss for the independent weft-supply for the side sections. A handsome effect may also be readily produced when one of the side sections is omitted—that is, in a two-section fabric when the weft is in sections contrasting in color. In 60 this case one-half of the fabric-face would be formed from weft from the shuttle and the other half of weft from an outside supply. The meeting edges of the two contrasting colors in the center of the fabric may either 65 be a straight line or may be given any fanciful design or contour, as desired.

What I claim is—

1. A double-faced elastic woven fabric comprising fibrous and rubber warps, a body-section composed of a weft-thread interwoven with a portion of said warps, and a side section composed of a portion of said warps and a separate weft interlocked with the weft of the said body-section. 80

2. A double-faced elastic woven fabric comprising fibrous and rubber warps, a central or body section composed of a weft-thread interwoven with a portion of said warps, and two side sections each of which is 90 composed of a portion of said warps and a separate weft-thread interlocked with the weft of the said central or body section. 85

3. A double-faced elastic woven fabric comprising fibrous and rubber warps, a body-section composed of a weft-thread interwoven with a portion of said warps, and a side section composed of a portion of said warps and a separate weft interlocked with the weft of the said body-section, the outer rubber warp 95 of said side section being at the extreme edge 100 of the fabric next the overlying side-section weft.

4. A double-faced elastic woven fabric comprising fibrous and rubber warps, a central or body section composed of a weft-thread interwoven with a portion of said warps, and two side sections each of which is 105 composed of a portion of said warps and a separate weft-thread interlocked with the 110 weft of the said central or body section, the outer rubber warps of said side sections being at the extreme edges of the fabric next the overlying side-section wefts.

In testimony whereof I affix my signature 115 in presence of two witnesses.

GEORGE C. MOORE.
